(57) **CLAIM**

The ornamental design for a rattan plant stand, as shown and described.

DESCRIPTION

FIG. 1 is a perspective view of a rattan plant stand, in accordance with my new design;

FIG. 2 is a top plan view of the rattan plant stand of FIG. 1; FIG. 3 is a first bottom plan view of the rattan plant stand of FIG. 1;

FIG. 4 is a second bottom plan view of the rattan plant stand of FIG. 1 with the leg stand rotated in an alternate position than that shown in FIG. 3;

FIG. 5 is a bottom plan view of a plant saucer for the rattan plant stand of FIG. 1 shown separately from the leg stand for ease of illustration view thereof;

FIG. 6 is a bottom plan view of a leg assembly of the rattan plant stand of FIG. 1 shown separately from the rattan saucer for ease of illustration; and,

FIG. 7 is a top plan view of the leg assembly of the rattan plant stand of FIG. 6.
